[57] CLAIM

The ornamental design for a covered swivel card file, as shown and described.

DESCRIPTION

FIG. 1 is a front side perspective view of a covered swivel card file showing our new design, the file being shown in closed condition.

FIG. 2 is a front side perspective view thereof with the file shown in open condition.

FIG. 3 is a front side perspective view thereof with the file shown in open condition and with cards removed.

FIG. 4 is a rear side perspective view thereof with the file shown in closed condition, and

FIG. 5 is a bottom plan view thereof.

The card file is characterized in that the casing and cover are at least semitransparent.

FIG. 1

FIG. 2

FIG. 3

FIG. 4

FIG. 5
